UNITED STATES PATENT OFFICE.

ORIE E. PHILBRICK, OF BARRE, VERMONT, ASSIGNOR TO SMITH, WHITCOMB & COOK CO., OF BARRE, VERMONT, A CORPORATION OF VERMONT.

STONE-POLISHING WHEEL.

1,404,139.

Specification of Letters Patent. Patented Jan. 17, 1922.

Application filed November 20, 1920. Serial No. 425,427.

To all whom it may concern:

Be it known that I, ORIE E. PHILBRICK, a citizen of the United States, and resident of Barre, in the county of Washington and State of Vermont, have invented certain new and useful Improvements in Stone-Polishing Wheels, of which the following is a specification.

My invention relates to polishing wheels 10 of that type embodying a head or plate of disk form having scroll shaped flanges on one face thereof for working an abrasive against a surface of a block of stone whereby the same is reduced to proper condition 15 for subsequent buffing.

Polishing wheels of this general type are extensively used for stone polishing purposes in preference to other types of wheels because scroll shaped flanges have been 20 found to possess many well known advantages over other types of flanges, but even scroll flanged wheels have proven more or less deficient principally because their construction usually causes a fast feed of the 25 abrasive towards the center of the wheel with a resultant banking up of the abrasive and in many instances the breaking or chipping of the edges of the stone, or else, when constructed to partially eliminate these 30 disadvantages, the feed of the abrasive to the flanges is slow with a resultant slow cutting of the stone and a wearing away of the flanges out of proportion to the amount of work accomplished.

My invention aims to overcome the aforementioned disadvantages by providing a 35 polishing wheel having scroll flanges so arranged that there is a free feed of the abrasive to the flanges and yet any tendency of 40 the abrasive to bank up due to its fast feed toward the center of the wheel is eliminated, whereby fast cutting with minimum wear to the flanges is accomplished without breaking or chipping the edges of the stone 45 being dressed.

A further important object of my invention is to provide a head or plate having 50 grooves cut in the under face thereof so as to extend contiguous to a flange or flanges 55 adapted to be detachably secured to the plate, which flanges may be of any desired configuration, my purpose being to provide

a free passage between the flanges for the abrasive at all times, particularly when the flanges have become worn down to and beyond an extent that heretofore has required the substitution of new flanges. This feature of my invention thus introduces a factor of economy in stone surfacing which is of manifest and exceptional importance. 60

The essential characteristics of my improved polishing wheel, whereby all of the foregoing is accomplished are illustrated in a preferred form in the accompanying drawing, but it is to be understood that various minor modifications as well as desirable additions may be made in and to the structure shown within the scope of my invention as defined in the appended claims. 65

In the drawings, wherein like characters 70 of reference denote corresponding parts in the separate views—

Fig. 1 is a bottom view of a polishing wheel embodying the novel and essential features of my invention; and 75

Fig. 2 is a transverse section through the wheel taken on the line 2—2 of Fig. 1.

Referring to the drawings in detail, 10 designates the head or plate of my improved wheel which is of the usual disc form having an opening 11 in the center thereof and provided with any desired means (not shown) whereby it may be attached to a driving shaft for rotating and bodily moving the same over a surface to be dressed or 15 polished. This plate is of novel construction, as is also the relative arrangement of any desired number of sets of lead, intermediate and inner scroll flanges 12, 13 and 14, respectively, which are preferably detachably secured to the under face thereof, as by means of bolts 15 passing down through the plate and threaded into openings in the flanges, there preferably being two sets of these flanges, as shown, although as will be 20 obvious a greater number of sets may be provided if desired. 90

By reference to Figure 1 of the drawing it will be observed that the lead ends of the inner flanges 14 are disposed at diametrically 100 opposite points on the plate 10 intermediate the center of the latter and its periphery, and that from their lead ends these inner flanges extend at a constant pitch spirally

inward and terminate near the opening 11, being nested one within the other in relative spaced relation as shown.

The intermediate flanges 13 are spaced 5 outward with respect to the inner flanges 12 and follow the curvature of the latter, their inner ends terminating in spaced relation to the lead ends of the inner flanges and their lead ends being disposed slightly for- 10 ward of the lead ends of said inner flanges and intermediate the latter and the periphery of the plate.

The respective lead flanges 12 preferably have their lead ends disposed substantially 15 flush with the periphery of the plate 10 at points substantially in radial alignment with the respective inner ends of the intermediate flanges, from whence they are curved spirally inward at a constant pitch throughout 20 the major portion of their length so as to extend one in spaced relation to each intermediate flange 13, but as said lead flanges approach points in substantial radial alignment with the inner ends, respectively, of 25 the intermediate flanges they begin to curve abruptly inward, which abrupt curve is continued, as at 16, to the inner ends of said lead flanges, the said inner end of each lead flange being disposed between and substan- 30 tially aligned with the lead end of an inner flange 14 and an adjacent inner end of an intermediate flange 13, and in spaced relation to an adjacent lead end of an intermediate flange, as well as in spaced relation 35 with the lead end of one of the inner flanges and an intermediate portion of the other inner flange which intermediate portion of the latter inner flange is disposed between the inner end of the lead flange and the center 40 of the plate, as shown.

The lead end of each of the flanges is preferably curved to permit the abrasive to pass freely under the flanges during rotation of the wheel and, as shown, the lead ends of 45 the lead flanges are sharpened so as to gather the abrasive and direct it between the flanges, in which connection it will be observed that a free feed passage is provided between the lead ends and the abruptly inturned ends of 50 the respective lead flanges to direct the abrasive into all of the channels between the flanges as shown by the arrows in Fig. 1. It will also be observed that after entering the channels the abrasive must travel at least a 55 distance equivalent to a full revolution of the wheel before it can reach the center of the latter. The result is that a maximum amount of abrasive is carried by the wheel at all times, thus insuring fast cutting with 60 minimum wear upon the flanges, and at the same time, due to the necessary long distance the abrasive must travel to reach the center of the wheel, banking up of the same and chipping of the stone being polished is 65 avoided.

Scroll flanges when constructed and arranged in accordance with the foregoing may be mounted upon any desired type of base plate, but I prefer to use them in conjunction with a plate of the type illustrated 70 to advantage in Fig. 2 of the drawing. This plate is of novel construction in that it is provided upon its under face with grooves 17 which extend contiguous to the flanges 12, 13 and 14 and in effect provide arched 75 spaces between adjacent flanges, bosses 18 being thus formed between adjacent grooves to which the flanges may be secured. By such a construction it is apparent that a free passage is maintained between the flanges, 80 even after the same have worn down to and beyond an extent which heretofore has necessitated their replacement to avoid banking up or clogging of the channels. The base plate may have a single groove or a number 85 of grooves and, as is apparent, may be used in conjunction with types of scroll flanges other than those herein shown and described.

I claim—

1. A stone polishing wheel comprising a 90 plate, lead, intermediate and inner scrolls mounted thereon, the lead ends of the inner scrolls being spaced with respect to the inner ends of the intermediate scrolls, and the inner scrolls being interposed between said 95 spacements and the center of the wheel, the inner ends of the lead scrolls extending into said spacements.

2. A stone polishing wheel comprising a 100 plate, lead, intermediate and inner scrolls mounted thereon, the lead ends of the inner scrolls being spaced with respect to the inner ends of the intermediate scrolls, and the inner scrolls being interposed between said 105 spacements and the center of the wheel, the inner ends of the lead scrolls extending into said spacements and across adjacent ends of the inner and intermediate scrolls and terminating in spaced relation to the inter- 110 posed inner scrolls.

3. A stone polishing wheel comprising a plate, lead, intermediate and inner scrolls mounted thereon, the lead ends of the inner scrolls being spaced with respect to the inner ends of the intermediate scrolls, and the 115 inner scrolls being interposed between said spacements and the center of the wheel, the inner ends of the lead scrolls extending into said spacements and being disposed in spaced relation to the lead ends of the intermediate and inner scrolls.

4. A polishing wheel plate having a face thereof provided with a groove and adapted to have a flange secured thereto extending contiguous with the groove.

5. A polishing wheel plate having a face thereof provided with grooves forming correspondingly disposed ribs adapted to have flanges secured thereto extending contiguous with the grooves.

6. A polishing wheel plate having a face thereof provided with substantially spiral grooves forming ribs adapted to have flanges secured thereto extending contiguous 5 with the grooves.
7. A stone polishing wheel comprising a plate, lead intermediate and inner scrolls mounted thereon, the lead ends of the inner scrolls being spaced with respect to the inner end of the intermediate scrolls, the inner 10 scrolls being interposed between said spacements and the center of the wheel and completely encircling said wheel center, and the inner ends of the lead scrolls extending into said spacements. 15

In testimony whereof I hereunto affix my signature.

ORIE E. PHILBRICK.
